US0D1103106S

(12) **United States Design Patent** (10) **Patent No.:** **US D1,103,106 S**
(45) **Date of Patent:** **** Nov. 25, 2025**

(54) **MAGNETIC CORE**

(71) Applicant: **Delta Electronics (Shanghai) CO., LTD**, Shanghai (CN)
(72) Inventors: **Zengyi Lu**, Shanghai (CN); **Haibin Song**, Shanghai (CN); **Shiwei Liu**, Shanghai (CN); **Daofei Xu**, Shanghai (CN); **Jinfa Zhang**, Shanghai (CN)

(73) Assignee: **Delta Electronics (Shanghai) CO., LTD.**, Shanghai (CN)

(**) Term: **15 Years**

(21) Appl. No.: **29/801,131**

(22) Filed: **Jul. 27, 2021**

Related U.S. Application Data

(62) Division of application No. 29/673,239, filed on Dec. 13, 2018, now Pat. No. Des. 932,435.

(57) **CLAIM**

The ornamental design for a magnetic core as shown and described.

DESCRIPTION

The Sole FIGURE is a perspective view of a magnetic core showing the new design.

The broken lines illustrate portions of the magnetic core that form no part of the claimed design.

1 Claim, 1 Drawing Sheet
